UNITED STATES PATENT OFFICE.

GEORGE C. BEIDLER, OF OKLAHOMA, OKLAHOMA.

PHOTOGRAPHING AND DEVELOPING APPARATUS.

1,160,241.

Specification of Letters Patent. Patented Nov. 16, 1915.

Application filed July 10, 1908. Serial No. 442,877.

To all whom it may concern:

Be it known that I, GEORGE C. BEIDLER, a citizen of the United States of America, residing at Oklahoma, in the county and State of Oklahoma, have invented certain new and useful Improvements in Photographing and Developing Apparatus, of which the following is a specification.

This invention relates to photographing and developing apparatus and more particularly to an improvement designed to simplify the construction of the apparatus patented to me on the 23d day of January, 1906, numbered 810,388.

An object of this invention is to produce a photographing and developing apparatus with the developing means in operative relation to the photographing apparatus having a tank or receptacle to contain developing fluid, with relation to which the drum rotates, the said drum displacing the developing fluid to such an extent as to make it possible to use a minimum quantity of the developing fluid for the purpose of immersing a film.

A further object of the invention is to provide a conveyer or carrying device preferably comprising a perforated apron or belt with which a flexible device such as a chain or the like coacts to retain the film on the apron or belt while the said film is being carried through the developing fluid.

I have found that an apparatus made in accordance with this invention will require a very short belt or apron for the reason that a single developing tank is employed and the film is delivered to a pan or receptacle containing the fixing fluid and instead of conveying the films through a tank containing the fixing fluid, the said films are simply delivered to the fixing fluid and are allowed to sink therein and they may be removed by hand at the convenience of the operator. In using this apparatus, it is of course desirable to wash the films after they are removed from the fixing fluid and that can be accomplished in any suitable way.

By the term "film" herein mentioned, I mean any photographically sensitized element capable of being treated in an apparatus of the character indicated.

With the foregoing and other objects in view, the invention consists in the details of construction and in the arrangement and combination of parts to be hereinafter more fully set forth and claimed.

In describing the invention in detail, reference will be had to the accompanying drawings forming part of this specification wherein like characters denote corresponding parts in the several views, in which—

Figure 1, is a view in elevation of the front of an apparatus embodying the invention; Fig. 2, is an end view of the developing apparatus with the casing removed; Fig. 3, is a similar view looking at the end opposite to that shown in Fig. 2 the receptacle for the fixing fluid being omitted; Fig. 4, is an enlarged detail view of the arresting mechanism and the controller for the feeding mechanism. Fig. 5 illustrates an enlarged sectional view of the internal mechanism of the apparatus, the hood being omitted and the receptacle being in elevation; Fig. 6 illustrates a fragment of a hood. Fig. 7 illustrates a view in elevation of a fragment of the casing, showing the manner of hinging the same to the base. Fig. 8 illustrates a perspective view of the lever for operating the dog.

In these drawings A, indicates a casing for the developing apparatus covered by a magazine B, adapted to contain a supply of film. The side of the magazine has an exposing chamber C, and a camera D, is applied to the side of the magazine for exposing the film in the exposing chamber to light.

The construction of the magazine, exposing chamber and camera may be similar to the same parts disclosed in my patent hereinbefore referred to, and will, therefore, not be described in detail. The magazine is preferably above the casing A, and acts as a cover for said casing. The front a, of the casing is stationary with relation to the base a', whereas the sides and back are connected to the magazine, and the back has hinges a² by which it is connected to the base, thus allowing the sides and back of the casing to be swung rearwardly with the magazine for the purpose of permitting access to the interior of the casing.

One side of the casing has an opening a², and below the opening brackets similar to the bracket a³, are attached to the casing. A pan or receptacle a⁴, is supported by the brackets a³, and said pan projects into the casing through the opening a². The purpose of the receptacle a⁴, is to contain a fixing fluid into which developed films are delivered. Under ordinary conditions, the

light would not be sufficiently strong to effect a developed film coming from the developing apparatus (to be hereinafter described) but for the purpose of providing a safe-guard against action of light on the developed film, a hood a^5 , is removably secured to the casing by studs, screws, or other attaching devices a^6 , entering button hole slots a^7 , in said hood. By this means, the hood 10 may be applied to the casing and removed therefrom.

The casing contains a tank or receptacle E , adapted to receive developing fluid, and said tank may have ends e , in which the 15 shafts F and G , are journaled, or said shafts may be suitably journaled otherwise in operative relation to the receptacle.

The receptacle may be supported by the plates H , secured to the base, and said receptacle has a drain pipe I , to which the cock J , is connected, said cock extending through 20 the front of the casing. A drip pan K , is located under the receptacle and is provided with a drain nipple k , extending through 25 the base. The drip pan is provided to collect the drippings from the chains, conveyors and rollers, to be presently described. Shafts k' , extend between the plates H , and support the pan K , and said shafts carry 30 pulleys k^2 , over which said chains travel. The shaft F , is extended through the front of the casing and may be provided with a crank f' , by which the shaft is rotated, or the said shaft may be rotated in any other 35 approved manner.

The rear ends of the shafts F and G , have sprocket wheels f and g , respectively and said sprocket wheels are connected by a sprocket chain M , by which motion of the 40 shaft F , is communicated to the shaft G .

A frame N , is removably supported above the receptacle and said frame has a depending arm n , at each end forming supports for the rotatable drum O . The drum may 45 be hollow and is preferably comparatively large with respect to the receptacle in which it is supported, for, by this construction, the developing fluid contained in the receptacle is displaced and a small quantity of 50 the developing fluid will be sufficient to completely immerse a film as it is carried by the drum. One end of the drum is provided with a peripheral gear P , meshing with a pinion Q , rotatable on a stud q , projecting from one of the arms. The pinion Q , is driven by a gear wheel R , on a shaft S , the said gear wheel R , taking motion 55 from a gear wheel R' , mounted on the shaft G .

60 The end of the drum opposite the peripheral gear P , is recessed to form a shoulder T , and said shoulder is engaged by a dog U , which is slidably mounted on a stud V , the said dog being pulled downwardly by 65 the spring v . Under ordinary conditions,

the weight of the dog will be sufficient to cause it to move longitudinally, but in order to insure positive action the spring v , is provided. The object of the dog U , is to arrest the drum at each complete rotation 70 of the said drum and as the shoulder of the drum contacts the end of the dog, the dog is elevated slightly until it has moved a distance equal to the length of the slot v' . By this arrangement, the mechanism is 75 brought to rest at such time as the film is immersed in the developing fluid contained in the tank and the mechanism cannot be again operated until the dog U , is moved out of engagement with the shoulder T . 80 This is accomplished by the lever W , shown in Fig. 8 which is journaled in the front of the casing and bears against one edge of the dog. Pressure on the outer end of the lever results in pressure on the upper 85 end of the dog, which will cause the lower end of the dog to swing out of engagement with the shoulder. When the lower end of the dog is clear of the shoulder T , it is free to drop so that its end clears the shoulder 90 T , of the drum and the mechanism is then free to be operated through the medium of the crank or other device for applying power. The periphery of the drum being cut away as indicated, also permits the arm 95 X , to be moved with relation to the dog w , on the feeding and cutting roller to be hereinafter referred to.

The arm X , is held normally drawn down by means of the spring x , and when the 100 drum rotates sufficiently to bring the recessed portion thereof under the arm X , said arm is drawn down so that its upper end clears the end of the dog w . When the dog is released, the spring w' forces its nose 105 into engagement with the ratchet wheel Y , on the shaft y , and hence rotation of the shaft is communicated to the feeding roller Z , it being understood that the dog w , is pivoted on the feeding roller and that the 110 spring w' , holds the nose of the dog normally in engagement with the ratchet wheel Y .

For the purpose of holding the arm X , normally elevated a cam Z' , is mounted on 115 the frame N , and may be moved to hold the arm normally elevated in which position the said arm will hold the dog out of engagement with the ratchet wheel and the shaft y , may be rotated without operating the feeding roller. The cam Z' is turned by the button Z'' which latter is outside the casing and the said cam is caused to engage or release the arm by the rotation of the 120 said button.

When a film is caused to travel between the feeding roller Z , and the roller z , it is punctured at each rotation of the feeding roller by the serrated blade Z^2 , on the feeding roller and the film is then directed be- 130

tween the two rollers z' and z^2 , and from there to the interior of the developing apparatus where the film is delivered to the conveyer, consisting of the chain S and the 5 perforated belt S².

In operation, when the parts are in the position shown in Fig. 2, the cam Z' is moved to disengage the arm X, and the lever W is pressed to throw the end of the 10 dog U out of engagement with the shoulder T. The dog is then moved longitudinally and passes the shoulder T so that the drum is free to rotate, power being applied to the shaft F, the shaft G is rotated 15 through the medium of the sprocket wheels and chain and the gear wheel R taking motion from the shaft G heretofore described, turn the gear wheel Q and communicates motion to the drum. When the drum has 20 been rotated slightly, the arm X descends in the recess of the drum and the upper end of said arm clears the dog w and permits the spring to force the nose of the dog into engagement with the ratchet wheel. By this 25 means, the motion of the shaft y is communicated to the feeding and cutting roller Z and the film is drawn between the roller Z and the roller z and punctured, that is to say a film is punctured with each complete 30 rotation of the roller Z, and said film is directed between the rollers z' and z^2 . After the arm X has been elevated to the periphery of the drum the upper end of the drum stands in the path of travel of the dog w 35 as it is carried around by the feeding and cutting roller Z, and when the said dog contacts the arm, the nose of the dog is thrown out of engagement with the ratchet wheel and the shaft y is permitted to rotate independently of the feeding and cutting roller. 40 Though the feeding and cutting roller comes to rest, the rollers z' and z^2 continue to rotate, drawing the film downward and causing the film in engagement with the 45 said rollers z' and z^2 to be severed from the body of the film on the puncture line heretofore referred to. The film thus severed is delivered to the conveyer consisting of the chain and belt heretofore mentioned. 50 The shaft y, is driven through the medium of the gear wheel y', meshing with a gear wheel y², on the end of the roller z' .

The roller Z, is positively driven by a gear wheel z^3 , meshing with the periphery gear 55 z^4 , on the feeding and cutting roller Z, and the rollers z' and z^2 , are preferably positively driven by being geared together at one end.

The frame N, is provided with a roller 60 N', which is relatively small around which a belt or apron travels, and it has been found in practice that a film after having been carried through the developing tank by means of the belt or apron and the chains 65 which hold the film on the belt or apron,

and said film being saturated, will adhere to the surface of the belt or apron to a sufficient extent to cause the said film to travel with the belt or apron from the point of disengagement of the chain with the film, 70 which is at the shaft F, until the said belt or apron starts to encircle the roller N', but owing to the abruptness of the turn over the roller, the said film breaks away from the belt or apron and will, by gravity, descend 75 into the pan or receptacle a⁴, which contains the fixing fluid. It has been found that the film, as it is fed from the developing apparatus, will be supported by the fixing fluid in the tank or receptacle and will 80 travel longitudinally of the pan as it is being fed from the developing apparatus. In other words, the edge of the film will not fall into the pan or receptacle vertically, but will travel sufficiently therein to cause the 85 said film to lie flat in the contents of said pan or receptacle, so that the prints will lie one upon the other therein.

I claim—

1. In a photographing and developing apparatus, a receptacle for containing developer, a drum rotatably supported in the receptacle, a conveyer traveling on the drum, means for delivering prints to the conveyer, a dog for engaging and arresting the drum, 90 means for disengaging the dog from the drum, an arm actuated by the drum, and film feeding mechanism controlled by the arm.

2. In a photographing and developing apparatus, a receptacle adapted to contain developer, a drum rotatably supported in the receptacle, means for rotating the drum, a dog engaging the drum for intermittently arresting said drum, means for disengaging 100 the dog from the drum, an arm actuated by the drum, a cutting mechanism, and means whereby the movement of the arm radially of the drum controls the cutting mechanism.

3. In a photographing and developing apparatus, a receptacle adapted to contain developer, a drum rotatably supported therein, said drum having a peripheral recess forming a shoulder, a dog engaging 115 the shoulder for arresting the drum, means for disengaging the dog and drum, an arm actuated by the drum, a cutting mechanism, and means for connecting the cutting mechanism and the source of power, the said arm 120 controlling the connection between the cutting mechanism and the source of power.

4. In a photographing and developing apparatus, a receptacle adapted to contain developer fluid, a drum rotatably supported 125 therein, said drum having a peripheral recess terminating in a shoulder, a dog adapted to engage the shoulder, means for disengaging the dog from the shoulder and permitting it to remain out of operative rela- 130

tion with the shoulder, an arm moved by the rotating drum, a film cutting mechanism, means for connecting the film cutting mechanism to a source of power, and means whereby the arm controls the connection between the film cutting mechanism and the source of power.

5. In a photographing and developing apparatus, a receptacle adapted to contain developer, a drum rotatably supported therein, said drum having a peripheral recess forming a shoulder, means for rotating the drum, means coating with the drum for carrying film, means for delivering film to the means for carrying film, a film cutting mechanism, means for connecting the film cutting mechanism and the source of power, and means actuated by the drum for controlling the connection between the film cutting mechanism and the source of power.

6. In a photographing and developing apparatus, a receptacle, a drum rotatably supported therein, a conveyer operating in conjunction with the drum, means for delivering film to the conveyer, means for cutting film, a source of power for the film cutting means, and an arm actuated by the drum for controlling the connection between the source of power and the film cutting means.

30 7. In a photgraphing and developing apparatus, means for delivering and cutting film, a developing apparatus having a drum with a peripheral shoulder, a conveyer operating in conjunction with the drum, means for delivering film to the conveyer, a dog having oscillating and reciprocating motion with respect to the drum adapted to engage the shoulder of the drum, means for moving the dog out of engagement with the shoulder of the drum, means for moving the dog longitudinally to cause its end to pass the shoulder of the drum, and suitably actuated means for controlling the means for cutting and delivering paper.

45 8. In a photographing and developing apparatus, a receptacle for developing fluid, a drum rotatably mounted therein, said drum having a recess forming a shoulder, and arm adapted to ride on the periphery of the drum and to reciprocate with relation thereto by entering the recess of said drum, a cutting mechanism, a source of power, means for connecting the source of power to the cutting mechanism, and means whereby the arm controls the means for connecting the cutting mechanism and the source of power.

9. In a photographing and developing apparatus, a receptacle adapted to contain developer, a drum rotatably supported therein, a conveyer acting in conjunction with the drum, a delivering mechanism in operative relation to the conveyer, a cutting mechanism in operative relation to the delivering mechanism, means for engaging and operating the cutting mechanism, means whereby

the drum is intermittently arrested, and means whereby the cutting mechanism is intermittently released.

10. In a photographing and developing apparatus, a receptacle adapted to contain developer, a member rotatably supported therein, a film feeding mechanism associated with the drum, an arm moved by the member and means engaged by the arm for controlling the film feeding mechanism.

11. In a photographing and developing apparatus, a receptacle for containing a developer, a drum mounted to rotate therein, said drum having a shoulder, a dog for engaging the shoulder to arrest the drum, means for mounting the dog and permitting pivotal and sliding movement whereby as the dog disengages the shoulder it moves longitudinally beyond the plane of the shoulder.

12. In a photographing and developing apparatus, a rotating member, a conveyer run thereon, an arm moved by the rotating member, means for delivering film to the conveyer, means for severing the film, means for rotating the severing means, a connection between the severing means and the rotating means and means whereby the arm controls the connection between the severing means and its rotating means.

13. In a photographing and developing apparatus, a receptacle for containing developer, a drum rotatable therein, a conveyer run on the drum, means for severing film, means for delivering film to the conveyer, means for actuating the film severing means, and means operated by the drum for controlling the film severing means.

14. In a photographing and developing apparatus, a receptacle for containing developer, a member rotatable therein, means for turning the member, means for delivering film to the member, a film cutting mechanism, a source of power for the film cutting mechanism, and means actuated by the member for controlling the connection between the film cutting mechanism and the source of power.

15. In a photographing and developing apparatus, a receptacle adapted to contain developer, a drum rotatable therein, means acting with the drum for carrying film, cutting mechanism, a delivering mechanism acting in conjunction with the cutting mechanism before delivering film to the drum and its coating carrying device, means whereby the drum is intermittently arrested, and means whereby the cutting mechanism is intermittently released.

16. In a photographing and developing apparatus, a receptacle adapted to contain developer, a drum rotatable therein, means acting with the drum for carrying film, cutting mechanism, a delivering mechanism acting in conjunction with the cutting mecha-

nism before delivering film to the drum and its coacting carrying means, means whereby the drum is intermittently arrested, and means actuated by the drum for intermittently releasing the cutting mechanism.

17. In a photographing and developing apparatus, a receptacle for containing developer, a rotatable member therein, means for severing film, means actuating in conjunction with the rotatable member for carrying film, means for delivering severed film to the rotatable member and its coacting carrier, means for operating the film severing means, means actuated by the rotatable member for releasing the film severing means, and means for arresting the rotatable member.
18. In a photographing and developing apparatus, a receptacle for containing developer, a member rotatably supported in the receptacle, means for rotating said member, means for intermittently arresting the member, an arm actuated by the member, a cutting mechanism, and means engaged by the arm adapted to control the cutting mechanism.

Copies of this patent may be obtained for five cents each, by addressing the "Commissioner of Patents, Washington, D. C."

19. In a photographing and developing apparatus, a rotatable member, cutting mechanism, means acting with the rotatable member for carrying sections of film, means for delivering film to the rotatable member and its coacting carrier, means for actuating the cutting mechanism, and an arm moved by the rotatable member controlling the means for actuating the cutting mechanism.

20. In a photographing and developing apparatus, a receptacle for containing developer, a member rotatable therein, means acting in conjunction with the rotatable member for carrying film, a film severing means, means for delivering film to the film carrying means, means for actuating the film severing means and means operated by the rotatable member for controlling the film severing means.

In testimony whereof I affix my signature in the presence of two witnesses.

GEORGE C. BEIDLER.
